CHARLES F. ROBBINS, OF WASHINGTON, DISTRICT OF COLUMBIA.

THERMO-OPERATED DILUTING-VALVE FOR CARBURETERS.

1,197,545.

Specification of Letters Patent.

Patented Sept. 5, 1916.

Application filed March 9, 1914. Serial No. 823,541.

To all whom it may concern:

Be it known that I, CHARLES F. ROBBINS, a citizen of the United States, residing at Washington, District of Columbia, have 5 invented new and useful Improvements in Thermo-Operated Diluting-Valves for Carbureters, of which the following is a specification.

This invention has to deal with carbureter 10 regulation whereby the proper explosive mixture both for starting and running conditions will be produced at all times irrespectively of daily and seasonal temperature changes; and the invention relates more particularly to mixture diluting means of that 15 type including a thermo-responsive means which varies automatically the proportion of air to fuel according to atmospheric temperature variations, reducing or shutting off the 20 diluting air as the temperature falls from a given point or increasing the amount as the temperature rises for the purpose of insuring an efficient and economical mixture.

The general object of this invention is to 25 combine with a carbureter, having main and secondary air admitting means, a tertiary air admitting means of simple, efficient and novel form which is thermally actuated so that with variations from warm to cold 30 weather, or vice versa, the tertiary air admitting means will close or open more or less as conditions require to maintain a proper fuel mixture.

Another object is to so design the thermo- 35 responsive mixture diluting device that it can be applied to any carbureter as an attachment in an extremely simple manner and with highly beneficial results, in regard to fuel consumption, improved running of 40 the engine, elimination of starting troubles in cold weather, and avoiding hand adjustment of the secondary air valve with temperature changes.

The carrying out of the invention will be 45 more fully set forth hereinafter, in connection with the accompanying drawing and the novel features will be defined in the appended claims.

In the drawings: Figure 1 is a side view 50 of a carbureter with the improved mixture diluter applied thereto. Figs. 2 and 3 are enlarged sectional views of the diluter removed. Fig. 4 is a side view of a carbureter

having a modified form of mixture diluter attached thereto. Fig. 5 is a plan view of 55 the attachment, and Fig. 6 is a perspective view of the diluting valve and its guide.

Referring to Fig. 1 of the drawing, A designates an ordinary carbureter and B the thermo-mixture diluter therefor, which is 60 shown in detail in Figs. 2 and 3. The carbureter comprises a mixture chamber I which has a main air inlet 2, and an auxiliary air inlet 3 controlled by a spring seated suction opened valve 4, to dilute the mixture 65 produced by the main air passing and drawing out fuel from the nozzle 5 that is controlled by a needle valve 6 and receives its supply from the bowl 7 wherein a constant fuel level is maintained by a float 8 connected with and controlling the fuel valve 9 for the fuel inlet pipe 10, the fuel mixture being supplied to an engine or other consumption means through the manifold 11 and the quantity of mixture being controlled by a 70 throttle 12. All that is necessary to be done to the carbureter, in order to attach the invention B thereto, is to drill and tap an opening 13 in the body of the carbureter at any suitable point so that air can be admitted to control the nature of the mixture to suit the requirements of temperature.

The attachment comprises a tertiary air admitting means, the inlets 2 and 3 being respectively the main and secondary air admitting means of the carbureter.

The attachment B comprises a drum or other chambered body 14 which is adapted to be connected by a pipe 15, or in any other manner with the opening 13 and atmospheric air is admitted to the body 14 through a port 16, the effective area of which is varied by a valve 17 controlled by and connected with a thermo-responsive device of any suitable character. The thermo-responsive device 18 shown is of the differentially expansive bimaterial type, fastened at one end to a bracket 19 and connected at the opposite end to the valve. The thermo-responsive device is curved around the body 14 so as to give 100 the desired range of action and yet take up but very little space. The free end of the thermo-responsive device has a resilient extension 20 which is bent in such a manner as to hold the valve 17 tensioned against or 105 seated on the outer peripheral surface of the

body 14 while the valve freely moves back and forth over the port 16 as the thermo-responsive device expands or contracts with the changes in temperature. The valve will 5 be closed at certain low temperatures and fully open at certain high temperatures and will be open more or less at intermediate temperatures. Thus in cold weather the tertiary air admitting means is inoperative 10 and does not dilute the mixture, but as the temperature increases, the valve of the tertiary admitting means opens to admit the proper amount of diluting air to the mixture in the carbureter and consequently efficient combustion and maximum power are 15 rendered possible.

To facilitate starting, a suction valve may be used to hold the port 16 closed until the engine runs by explosions. A valve 21 in 20 the form of a light leaf spring, is fastened in the body 14 with the free end of the spring covering the port 16. This valve will not uncover the port under the suction of the engine when cranking by hand to start 25 the engine, and hence too much air is prevented from entering the carbureter, when a rich starting mixture is required, but when the suction of the engine increases due to high speed after being started, the valve 21 30 will open and admit air provided the thermo-responsive device is holding the valve 17 open. A protective cap or casing 22 covers the body 14, valve 17 and thermo-responsive device 18, and this casing, which 35 has a threaded connection with the flange 23 of the body 14, has openings 24 to admit air to the port 16.

In the modified form of the thermally actuated mixture diluter shown in Figs. 4, 40 5, and 6, the thermo-responsive device 25 is mounted directly on the body of the carbureter C and the valve 26 that is connected with the thermo-responsive device is slideable in a guide 27 which is fastened to the carbureter at a port or opening 28. An adjustable connecting means 29 unites the valve with the thermo-responsive device whereby the proper set of the valve with respect to the port 28 may be obtained. In Fig. 5, the 45 valve, like the valve in Fig. 2, is shown partly open so that air is admitted to the carbureter, and as the temperature rises or lowers, the valve will open still further or move to closed position automatically 50 through the agency of the thermo-responsive device. Both forms of the device are extremely effective in practical operation.

The matter herein claimed is an improvement of the invention disclosed in my co-pending application, Serial Number 748,511, filed February 15, 1913.

What I claim as new, is:

1. The combination of a carbureter including main and secondary air admitting means, with a tertiary air admitting means

controlled by temperature variations, and comprising a unitary self-contained device attached to the carbureter.

2. The combination of a carbureter comprising a mixture producing means having 70 a single fuel supply operative independently of temperature conditions, a diluting air valve operated by difference in internal and external air pressure, a second diluting air valve, and a thermo-responsive device external to the carbureter and connected with the second valve to close and open the same according to temperature variations. 75

3. The combination of a carbureter having a mixing chamber provided with an air admitting means, with an attachment wholly exterior to the body of the carbureter and comprising a valve for controlling the amount of air admitted through said means to the mixing chamber, and a thermo-responsive device for actuating the said valve. 85

4. The combination of a carbureter, with a thermally controlled mixture diluting attachment communicating with the mixture chamber of the carbureter, said attachment being wholly outside the carbureter and comprising a valve closed at low temperature, and a thermo-responsive device for opening and closing the valve. 90

5. The combination of a carbureter, with 95 a thermally controlled mixture diluting attachment, comprising a port through which air is admitted to the carbureter, a suction actuated valve controlling the port and a thermally actuated valve for controlling the 100 port.

6. As a new article of manufacture, a unitary device embodying a thermo-responsive mixture diluting attachment for carbureters, comprising a ported body adapted to communicate with the mixture chamber of the carbureter, a valve for opening and closing the port, and a thermally responsive actuator for the valve. 105

7. A thermo-responsive mixture diluting 110 attachment for carbureters, comprising a ported body adapted to communicate with the mixture chamber of the carbureter, a valve for opening and closing the port, a thermally responsive actuator for the valve, 115 and a suction actuated valve controlling the said port.

8. A thermo-responsive mixture diluting device for a carbureter, comprising a chambered body having a port through which air 120 is admitted to the carbureter, a suction valve within the body for controlling the port, a valve outside the body for controlling the port, and a thermo-responsive device arranged to actuate the valve. 125

9. A thermo-responsive mixture diluting device for a carbureter, comprising a chambered body having a port through which air is admitted to the carbureter, a suction valve within the body for controlling the port, a 130

valve outside the body for controlling the port, a thermo-responsive device arranged to actuate the valve, and a protecting casing inclosing the second valve and thermo-responsive device.

10. The combination of a carbureter having a mixing chamber provided with a port in its wall through which air is admitted to dilute the mixture, a valve for controlling the port, a thermo-responsive device mounted outside the carbureter, and con-

nnections between the valve and thermo-responsive device and also located outside the carbureter.

In testimony whereof, I have signed my 15 name to this specification in the presence of two subscribing witnesses, this 9th day of March, 1914.

CHARLES F. ROBBINS.
